Primary Examiner—Antoine Duval Davis

[57] CLAIM

The design for test document for scanners, as shown and described.

DESCRIPTION

FIG. 1 is a view, in color, of a test document showing our new design;

FIG. 2 is a view, shaded for black and white, of the design shown in FIG. 1; and,

FIG. 3 is a view of an alternative embodiment of the design shown in FIG. 2.

The omitted views are flat, plain with no substantial thickness.
